UNITED STATES PATENT OFFICE.

CHARLES W. BREWSTER, OF NEW YORK, N. Y., ASSIGNOR TO THE BREWSTER-GOLDSMITH CORPORATION, INC., OF NEW YORK, N. Y., A CORPORATION OF NEW YORK.

SPARK PLUG.

Application filed July 5, 1918. Serial No. 243,395.

To all whom it may concern:

Be it known that I, CHARLES W. BREWSTER, a citizen of the United States, and a resident of the borough of Manhattan, in the city, county, and State of New York, have invented certain new and useful Improvements in Spark Plugs, of which the following is a specification.

The object of the invention is to provide an improved spark plug for internal combustion engines, and particularly for aeroplane engines, wherein the temperature and lubricating conditions are detrimental to ordinary plugs. To this end the invention may be said to comprise the parts, improvements and combinations hereinafter described and more particularly pointed out in the claims.

In the accompanying drawings:

Fig. 1 is an elevation of the spark plug with the valve and valve-retainer removed;

Fig. 2 is an axial section showing the valve seated in the position which it occupies during the compression stroke of the cylinder, and indicating a means for delivering a jet of liquid fuel into the intake;

Fig. 3 is a cross-section on the line 3—3 of Fig. 2;

Fig. 4 is a view looking at the inner end of the plug; and

Fig. 5 is an elevation of the central electrode unit.

The spark plug has a shell 1, which is screwed into an opening in the engine, as usual. The shell is provided in the upper part of its interior with a downward-facing beveled shoulder 2. An insulator 3 is inserted upward into the shell and is provided with a beveled centralizing shoulder 4 to co-operate with the shoulder 2. A central conductor rod 5 having a shoulder 6 at its lower end to bear upon the end of the insulator 3 passes through this insulator and projects above its top. An outer hollow insulator 7 encloses the projecting portion of the insulator 3 and rests upon the top of the shell. The parts are clamped together by a nut 8 screwed upon the upper end of the rod. This nut may be formed with a ball to receive an electrical connection of the glove-fastener type or any other suitable connection may be provided. The rod 5 preferably passes loosely through the insulator 3, and tight joints are insured by cement gaskets between the shoulders 2 and 4 and between the shoulder 6 and the end of the insulator.

The insulator 3 is desirably of porcelain, with an inner sleeve 9 of rolled mica to prevent leakage of current in event of cracking of the porcelain.

The central conductor rod 5 terminates a substantial distance above the mouth of the shell 1. Upon its end is a cup 10, the base of which forms the shoulder 6, to which reference has been made. This cup is preferably of substantially the same external diameter as the lower part of the insulator 3, and between these parts and the shell is an annular space 11. An outturned flange 12 on the edge of the cup 10 constitutes an electrode terminal, from which the spark passes to the shell at any point around the circumference. It will thus be seen that I provide an annular electrode presenting a hollow interior to the firing chamber and connected with the central conductor by a cup which recedes upward into the interior of the shell. The annular electrode is located inside the mouth of the shell as shown. In this way the central member presents the least amount of metal to the heat of the firing chamber and the terminal structure is protected within the shell. The cup 10 is preferably, though not necessarily, cylindrical, and its wall is made thin. The cup is advantageously made separately from the rod, but united integrally therewith by welding. The cup constitutes a barrier to prevent lubricating oil being thrown into the annular space between the central parts and the shell. In this connection, it will be noted that the gap between the annular electrode and the edge of the shell is too narrow to afford ready ingress for oil, and the slight amount which may enter is swept out by the means about to be described.

The construction described above, while advantageous where the temperatures are not too high and superior to ordinary designs, would not be sufficient in itself to prevent the electrode burning off under the extreme heat encountered in many aeroplane motors. Accordingly I combine with the foregoing features a means for passing a cleaning and cooling current through the annular passage 11. To this end a lateral intake 13 is formed in the upper part of the shell, this intake communicating with the said passage by a slotted opening 14, which is formed by a circular groove 15 in the interior of the shell, which groove constitutes a distributing

chamber at the upper end of the annular passage 11 and cuts through the side wall 16 at the region of the intake. A bushing 17 is screwed into the intake, outside of the 5 wall 16, and confines a check-valve 18. The said check-valve has a tubular skirt 19, which is guided in the passage of the bushing, and an enlarged head 20 which operates in the valve chamber 21, the laterally projecting rim of this head being formed with an annular beveled seat 22 which co-operates with a corresponding seat 23 formed at the inner end of the guide passage in the bushing. Openings 24 are cut through the skirt 15 19 adjacent the head of the valve.

In operation, on each suction stroke of the engine pistons the valve 18 is drawn inward, thus exposing the openings 24 to the chamber 21 and permitting air to rush into this 20 chamber and through the opening 14, which is not entirely covered by the head of the valve, into the interior of the plug, whence it passes downward through the annular passage 11 and around the ring electrode 25 12 into the firing chamber, thus effectively cooling the highly heated parts. For purposes of removing any deposits of grease and carbon in the plug, a small supply of gasoline is introduced with the air, but 30 instead of the gasoline and air entering the plug wholly as a vaporized mixture, means are provided for delivering the gasoline to the intake in liquid form, so that it is swept in at least partially in the condition 35 which is most effective for cutting greasy and carbonaceous deposits. In the illustrative form, a small pipe 25 connected with an elevated gasoline reservoir 26 extends in proximity to the open intake and is provided opposite it with a fine jet orifice 27. The very small stream of gasoline from this orifice plays continuously into the intake, and, upon each suction stroke of the piston of the corresponding engine cylinder, 40

the valve 18 opens and the small accumulation of gasoline is sprayed into the plug by the inrush of air. Needless to say, other specifically different forms of means for automatically delivering liquid fuel to the intake of the spark plug may be employed, 50 and I have found that under certain conditions the liquid fuel supply may be dispensed with and air alone used to cool and clean the plug.

One of the advantages of the invention 55 is that the plug is so effectively safeguarded against fouling that ordinary lubricating oil may be used for the engine cylinders in place of castor oil, the supply of which is limited.

It will be understood that in the foregoing specification "upper" means in the direction toward the part of the plug which is outside the engine, while "lower" means in the direction toward the part of the 65 plug which is inside the engine. Of course, the plug may be mounted in any position—vertically, horizontally, or at an inclination.

What I claim as new is:

The combination of a spark plug having 70 an interior cooling and cleaning passage and a suction intake thereto in the upper part of the plug, said intake having a valve chamber and a guide passage leading to said chamber, a check-valve having a tubular 75 skirt guided in said guide passage and provided with lateral openings, and an enlarged head operative in said chamber and having its projecting rim formed to seat at the end of the guide passage.

In testimony whereof, I have signed my name to this specification, in the presence of two subscribing witnesses.

CHARLES W. BREWSTER.
